UNITED STATES PATENT OFFICE.

GEORGE FREDERICK FORWOOD AND JOHN GILBERT TAPLAY, OF LONDON, ENGLAND,
ASSIGNORS TO UNITED KINGDOM OIL COMPANY LIMITED, OF LONDON, ENGLAND.

TREATMENT OF HYDROCARBONS.

Application filed July 5, 1921. Serial No. 482,552.

To all whom it may concern:

Be it known that GEORGE FREDERICK Forwood and JOHN GILBERT TAPLAY, subjects of the King of Great Britain, residing at 5 London, England, have invented certain new and useful Improvements in the Treatment of Hydrocarbons (for which I have filed an application in Great Britain, April 16, 1919), of which the following is a specification.

This invention consists in treating various oils of the hydrocarbon type, and having a high boiling point, at temperatures suitable for the particular oil to be treated, by passing their vapours mixed with steam or water vapour over hot carbon (wood peat or other vegetable or animal charcoal or such like carbonaceous matter) capable of decomposing the steam or water vapour when both the oil vapour and the steam or water vapour are at the same temperature, so that the carbon liberates hydrogen from the steam and the hydrogen is taken up by the oil, hydrogenating it, the object being to obtain an oil or spirit such as petrol suitable as a motor fuel or for other uses.

In order that the carbon shall be suitable it must be in a physical condition in which it will decompose steam or water vapour at the temperature used.

For the purpose of our invention we do not employ graphite retort carbon and coke.

In our previous British Patent Application No. 133,059 dated 12th December 1916 35 correspondent to United States Patent No. 1,440,286, granted December 26, 1922, and to which our present invention relates we have referred to treating hydrocarbon oils at a temperature of about 500° C. but with some 40 classes of oil it is preferred to use higher temperatures for efficiently cracking and hydrogenating such oils and these temperatures vary according to the class of oil to be treated.

45 For instance in treating paraffin oil, boiling point 140° to 320° C., we prefer a temperature of 550° to 600° C., kerosene oil, boiling point 180° to 350° C., we prefer a temperature of 600° to 630° C., solar oil, 50 boiling point 230° to 370° C., we prefer a temperature of 650° to 700° C., creosote oil, boiling point 180° to 270° C., we prefer a

temperature of 650° to 750° C., and anthracene oil, boiling point 270° to 400° C., 55 we prefer a temperature of 750° to 800° C., and with regard to some classes of heavy paraffin oils such as is used for fuel only, a temperature of 850° to 950° C. is requisite for the proper treatment and this is due to such oils having different compositions to 60 those already described although the boiling points and specific gravities of the fractions are similar.

In all cases the oil is forced through an injector into a retort in which the carbon is 65 heated where it is met by and mixed with the steam or water vapour, also under pressure, perfect atomization of the oil taking place at this point and the atomized oil and steam or water vapour passes through the 70 carbon in the retort, and the vapours leaving the retort are condensed and treated in the ordinary manner.

The foregoing process is not in the least 75 limited to any particular apparatus, but for the purpose of illustration, the drawing illustrates a sectional elevation of an apparatus suitable for carrying out the improved process or method.

Referring to this drawing in detail, A is 80 a tank for containing oil to be treated and has a pipe B connected thereto and leading from a suitable air compressor, not shown, and whereby air compression is passed to the tank to act upon the surface of the oil in the 85 latter. A pipe C extends downwardly into and near the bottom of the tank A and leads away from the top of the tank and connects with an injector nozzle D, adjacent to the attachment to the nozzle of a steam pipe E 90 leading from a suitable source of steam supply for mixing steam with the atomized or vapourized oil after it passes from the said injector D. Between the walls G of a furnace or heater a retort F is supported to an 95 angle and has its lower end connected to a continuation of the pipe C on the opposite side of the injector or nozzle D and in advance of the connection of the steam pipe E. Within the retort F is a perforated iron 100 stop plate adapted to support charcoal I in the retort at the lower end of the latter. From the upper end of the retort a pipe J extends and is connected by a branch pipe K

- and a dip pipe L to a hydraulic main M for passing the products of distillation from the retort into said main and causing the products to pass through the liquid in the main, 5 the main having an outlet N for oil and water. The gases and vapours, after passing through the seal in the hydraulic main M, are conveyed by a pipe P into a plurality of condensers Q, which are cooled by either 10 water or air to atmospheric temperature, the gases passing from one condenser to another through pipes R in the usual manner, the water and oils condensed from the gases falling into the receivers S from which they 15 pass through pipe T to a storage tank. The cooled gases, still containing uncondensed vapours of light spirits pass by way of pipe U to a scrubber V, for their removal. This scrubber is filled with broken brick, coke, 20 boards on edge or other known device for giving a large surface, and heavy oil is supplied to the top of the scrubber by the pipe W and sprayed on to the filling material, over the surface of which it falls to the bottom 25 of the scrubber meeting the gases and vapours travelling upwards through the scrubber, and freeing these from the spirit vapours still present. The oil containing the absorbed spirits passes to a storage tank 30 by the outlet pipe Y, and is distilled for recovery of the absorbed light spirit, and the scrubbed permanent gases pass away from the scrubber by the pipe b. Any liquid products separating from the gas passing 35 through the pipe U, and falling into the collecting chamber Z are removed by the siphon pipe a, and mixed with the liquid products from the condensers Q, Q, Q. It will be understood that the retort F may be 40 inclined in any such manner as renders it effective in the performance of its function, and that any type of condenser may be employed, and that other devices such as rotary or centrifugal washer may be employed in 45 place of scrubbers.
- To assist in the hydrogenation we may also admit steam or water vapour at various parts of the retort viz,
- (a) At right angles through the pipe c 50 to the stream of oil vapours and steam admitted through the injector at the back end of the retort F, or it may be admitted
  - (b) At such an angle through the pipe d as will cause it to meet the said vapours or 55 it may be admitted
  - (c) At such an angle as by the curved pipe e as will cause it to flow in the same direction as the said vapours, or it may be admitted
  - 60 (d) At the outlet end of the retort F as by the pipe f so that it flows against the stream of vapours aforesaid, or it may be admitted
  - (e) Simultaneously in all the directions 65 mentioned.

Although not absolutely necessary, it may be desirable to pre-heat the heavy oil, contained in the reservoir under pressure, by means of a steam coil fixed in the reservoir, or by passing the oil through a pipe heated by means of the waste gases from the furnace heating the retort containing the carbon, or by other means. The oil is, thereby rendered less viscous and will flow more readily. 70

It will be understood that anthracene and creosote are included for the purpose of the present specification under the term "hydrocarbon" as used in the claims hereto appended. 80

What we do claim as our invention and desire to secure by Letters Patent is:—

1. The process of treating hydrocarbon oils, having boiling points of 140° C. or more to obtain an oil or spirit suitable as motor fuel, consisting in atomizing the oil in a retort, mixing the same with water vapor or steam passed into said retort from a different direction to that at which said oil is introduced, passing the mixture over carbon in a light porous form maintained at a temperature varying from 550° C. to 950° C. according to the boiling point of the oil, the vapor of which is being treated. 90

2. The process of treating hydrocarbon oils, having boiling points of 140° C. or more to obtain an oil or spirit suitable as motor fuel, consisting in atomizing the oil in a retort, mixing the same with water vapor or steam passed into said retort from a plurality of different directions to that at which said oil is introduced, passing the mixture over carbon in a light porous form maintained at a temperature varying from 550° to 950° C. according to the boiling point of the oil, the vapor of which is being treated. 100

3. The process of treating kerosene, consisting in vaporizing same in a retort at the same time passing steam into said retort from a plurality of directions and conducting the mixture of steam and vaporized oil over carbon in a light porous form maintained at a temperature between 600 and 630° C. 110

4. The process of treating a hydrocarbon oil having a boiling point between 180° and 350° C., which comprises introducing such oil in one direction into a retort, concurrently introducing steam or water vapor into the retort in an opposite direction, mixing the oil in an atomized state in the retort with the steam or water vapor, and passing the oil and steam or water vapor over carbon in a light porous form while the latter and the oil and steam or water vapor are maintained at a temperature between 600° and 630° C. 120

5. The process of treating kerosene, consisting in vaporizing the same in a retort, 130

concurrently passing steam into said retort from an opposite direction and conducting the mixture of steam and vaporized oil over carbon in a light porous form while maintained at a temperature between 600 and 630° C.

In testimony whereof we have hereunto

set our hands in presence of two subscribing witnesses.
